UNITED STATES PATENT OFFICE.

FREDERICK MÜLLER, OF PHILADELPHIA, PENNSYLVANIA.

POCKET-BOOK, &c.

SPECIFICATION forming part of Letters Patent No. 476,159, dated May 31, 1892.

Application filed December 26, 1891. Serial No. 416,186. (No model.)

To all whom it may concern:

Be it known that I, FREDERICK MÜLLER, a citizen of the United States, and a resident of Philadelphia, Pennsylvania, have invented 5 certain Improvements in Pocket-Books, Card-Cases, &c., of which the following is a specification.

The object of my invention is to so construct the locking-device for the flap or overlying portion of a pocket-book, card-case, or the like, and to so combine said locking device with said overlying portion or flap that no part of the device will be exposed upon the outer face of the flap or cover, so that the latter is not disfigured by the exposure of the locking device, but can be ornamented in any way which the taste of the manufacturer may suggest or can be left entirely plain if ornamentation is not desired.

20 In the accompanying drawings, Figure 1 is a perspective view of a pocket-book provided with a locking device for the flap in accordance with my invention. Fig. 2 is an enlarged sectional view of the same. Fig. 3 is an enlarged transverse section of part of the flap with that element of the locking device which is carried thereby; and Fig. 4 is a perspective view on a still larger scale, showing the parts of the lock and lock-casing detached from 30 each other.

In Figs. 1, 2, and 3, A represents the flap of a pocket-book, and B the body of the book, these parts being locked together when the flap is closed. The locking device consists in 35 the present instance of a notched stem a, projecting upward from a plate b, secured to the outer pocket d of the body of the book, this notched stem being engaged by a bolt f, which slides and is guided in a casing carried by the 40 flap and comprising a box g and a cover-plate h, the bolt being acted upon by a spring i, which tends to project it and cause it to engage with the notched stem a, but said bolt having a head f', projecting beyond the flap, as shown in Figs. 1 and 2, so that the bolt can be pushed inward to release it from the notched stem and permit of the opening of the flap, the latter operation being effected by a 45 movement which is practically a continuation 50 of the movement necessary to release the bolt,

so that the unlocking and raising of the flap are readily accomplished. Usually in this class of goods the bolt and its casing are mounted upon the outside of the flap, which is perforated for the passage of the notched stem, and in the finer class of goods the presence of the bolt-casing on the outside of the flap is a disfigurement and in many cases interferes with the application of ornamental designs to the flap, or is equally objectionable 60 in cases where a plain flap is desired. In order to overcome this objection, therefore, I provide the flap with an inner layer or lining m and I secure the lock-casing to this inner layer or lining, so that the outer surface of 65 the flap is not mutilated nor is it marred by the presence of the lock-casing thereon..

As shown in the drawings, the cover-plate h of the lock-casing rests against the inner face of the inner layer or lining-piece m of the flap and has parallel slots n near its opposite edges, through which slots pass wings p, projecting upward from the opposite sides of the bolt-casing g, these wings passing through the slots in the cover-plate h, thence through like 75 slots in the inner layer or lining m of the flap, and being then turned down upon said lining, so as to serve not only to confine the cover-plate h to the casing g, but also to secure the entire lock-casing to the flap, the bent portions of the wings being embedded between the inner and outer layers of the flap, so that no portion of the lock-casing is exposed upon the surface.

The plate b, which carries the notched stem a, has fingers b', which are passed through the material of the outer pocket d of the body of the book and are bent down inside of the same, in order to secure the plate b in place, and it will be evident that, so far as the main object 85 of my invention is concerned, the plate b might be secured to the lining of the flap A and the lock-casing to the pocket d, although the construction shown is preferred, and it will also be manifest that my invention is applicable 90 to card-cases or the like, in which the flap or like part of the case is either of the character shown in the drawings or carries one or more pockets, that part of the locking device which is carried by the flap being, however, in all 100

cases secured to the innermost portion or layer of the flap, so as to prevent any exposure of the lock-casing on the surface.

Having thus described my invention, I claim and desire to secure by Letters Patent—

1. A pocket-book, card-case, or the like having a flap or overlying portion secured to the other portion or body by a locking device consisting of a notched stem and a sliding bolt, one element of said locking device being secured to the inner layer or lining of the flap by fastening devices, which are covered by the outer layer of said flap, whereby no portion of the locking device is exposed on the outer face of the flap, the locking-bolt projecting beyond the edge of said flap, substantially as specified.
2. A pocket-book, card-case, or the like having a flap or overlying portion secured to the other portion or body by a locking device con-

sisting of a notched stem and a sliding bolt, said flap carrying the sliding bolt and a casing and cover-plate therefor, said casing having wings passing through slots in the cover-plate and through the inner layer or lining of the flap, and said wings being turned down between the inner and outer layers of said flap so as to be covered by the outer layer, whereby the lock-case is secured together and to the flap without the exposure of any part of said case upon the outer face of the flap, substantially as specified.

In testimony whereof I have signed my name to this specification in the presence of two subscribing witnesses.

FREDERICK MÜLLER.
